GRINDING WHEEL TRUING APPARATUS

Carl G. Flygare, Worcester, Mass., assignor to
Norton Company, Worcester, Mass., a corpora-
tion of Massachusetts

Application February 19, 1938, Serial No. 191,497

8 Claims. (Cl. 125—11)

This invention relates to grinding machines, and more particularly to a grinding wheel truing apparatus for producing either a formed wheel, or producing a radius thereon, or a combination 5 radius and formed face.

One object of the invention is to provide a simple and thoroughly practical combined form and radial truing device for truing the operative face of a grinding wheel. Another object of the invention is to provide a truing device in which either an irregular formed face may be produced on the periphery of the wheel or a curved face of a definite radius, or if desired a combination 10 of an irregular formed face together with a radial face. Other objects will be in part obvious or in part pointed out hereinafter.

The invention accordingly consists in the features of construction, combinations of elements, and arrangements of parts, as will be exemplified 20 in the structure to be hereinafter described, and the scope of the application of which will be indicated in the following claims.

In the accompanying drawing in which is shown one of many possible embodiments of the 25 mechanical features of this invention,

Fig. 1 is a fragmentary cross-sectional view through a portion of a cylindrical grinding machine, showing the improved truing apparatus in end elevation;

Fig. 2 is a rear elevation of the truing apparatus shown in Fig. 1;

Fig. 3 is a fragmentary horizontal sectional view taken approximately on the line 3—3 of Fig. 1;

Fig. 4 is a longitudinal vertical sectional view through the truing apparatus traverse mechanism, taken approximately on the line 4—4 of Fig. 1;

Fig. 5 is a fragmentary detail view of the parts shown in Fig. 3, showing the truing tool at the opposite end of its traversing stroke;

Fig. 6 is a fragmentary detail view, showing the manner in which the parts are arranged for adjusting the truing tool for truing a predetermined radius on the wheel periphery; and

Fig. 7 shows a horizontal sectional view through a work holding chuck and headstock spindle.

A grinding machine has been illustrated in the drawing comprising a base 10 which supports a longitudinally traversable work table 11 on a V-way 12 and flat way 13. The table 11 is provided with a depending rack bar 14 which meshes with a rotatable gear 15. The gear 15 is mounted 55 on the outer end of a shaft 16 which is journaled

in a suitable bearing within the housing 17 which projects from the front of the machine base 10. A manually operable hand wheel 18 is mounted on the outer end of the shaft 16 and serves to facilitate a manual traversing of the table 11, either for a grinding operation or to traverse a truing tool across the periphery of the grinding wheel.

A rotatable grinding wheel 19 is mounted on a spindle (not shown) which in turn is supported 10 on a transversely movable wheel slide (not shown) which is fed transversely by means of a nut and screw feeding mechanism which may be actuated either automatically at either end of 15 the table stroke or manually by means of a manually operable hand wheel (not shown). These elements are not considered to be a part of the present invention and consequently have not been illustrated in detail. These well known grinding machine elements are clearly illustrated 20 and described in the prior United States patent to Norton No. 762,838 dated June 14, 1904.

A swivel table 20 of the well known type, such as used in common practice on cylindrical machines, is mounted on top of the table 11 and is 25 pivotally adjustable thereon to facilitate setting up the machine so that the work axis is parallel to or at an angle relative to the axis of rotation of the grinding wheel spindle.

In order to grind a work piece 21, such as that 30 shown in Fig. 7, a grinding wheel 19 is provided having its peripheral face formed in accordance with the shape of the periphery of the work piece. It is desirable to provide a truing apparatus to facilitate maintaining the grinding wheel face 35 in proper condition and in proper contour to produce a predetermined shape on successive pieces of work. The work piece to be ground is mounted in a rotatable headstock spindle 22 in a collet or chuck 23.

A truing apparatus is provided which may be readily applied to or removed from the machine before and after truing. The truing apparatus comprises a base member 30 which is clamped in adjusted position on the swivel table 20 by 45 means of a manually operable lever clamping mechanism 31. This lever operates through a toggle lever connection to rock a clamping arm 32 which engages the lower portion 33 of a dovetailed projection of the swivel table 20. An upper portion 34 of the dovetail is engaged by a substantially V-shaped recess in the base member 30.

An upper base member 35 is adjustably supported on the base 30 and is arranged to be 55

clamped thereon by means of the screws 38 and 37. The screw 37 passes through an elongated slot 39 in the upper base member 35 and is screw threaded in the base 30. The screw 36 passes through an elongated slot 38 in the upper base member 35, through an elongated arcuate slot 38a in the base member 30 and is provided with a nut at its lower end. The arcuate slot 38a is formed concentric with the screw 37 and serves to facilitate an angular adjustment of the upper base member 35 relative to the base 30.

A dovetailed slideway 40 is formed on the upper portion of the upper base member 35 which extends longitudinally in a direction substantially parallel to the swivel table. A slide 41 is provided with a mating dovetailed surface which mates with the dovetail 40 on the base member 35.

A traverse mechanism is provided for traversing the slide 41 longitudinally on the dovetailed slideway 40. This mechanism may comprise a rotatable screw 42 which is journaled in a bearing 43 in the upper base member 35. The screw 42 engages or meshes with a nut 44 which is fixedly supported on and depends from the under side of the slide 41. The outer end of the feed screw 42 is provided with a manually operable hand wheel 45 by means of which the screw 42 may be readily rotated in either direction to traverse the slide 41 longitudinally on its supporting dovetailed slideway 40.

A pivotally mounted truing tool support 50 is pivotally supported on a pair of opposed pointed screws 51 and 52 which are screw threaded into the bosses 53 and 54 which project from the slide 41. The pointed ends of the screws 51 and 52 engage countersunk apertures within the bosses 55 and 56 which are formed integral with the pivotally mounted supporting member 50.

A follower member 60 is adjustably mounted on the member 50 and is arranged to engage a forming bar 61 which is supported adjacent to the lower portion of the upper base member 35. The forming bar is provided with a surface of a predetermined contour to move the truing tool transversely during its traversing movement to produce a predetermined contour on the wheel face. A yieldable means, such as a compression spring 62, is interposed between a horizontally extending portion of the member 50 and the upper surface of the slide 41 and serves to maintain the follower 60 in operative engagement with the forming bar 61 during the traversing movement of the slide 41. The forming bar 61 is fastened to the lower part of the upper base member 35 within a pair of right angle plane surfaces 63 and is held in position thereon by means of screws 64.

A pair of horizontally arranged screws 65 are screw threaded into the upper base member and have their heads engaging notches cut in the upper surface of the forming bar 61. These screws 65 serve to aid in adjusting and locating the bar 61 before clamping it in place by means of the screws 64.

In order to grind a spherical surface on a work piece, it is desirable to produce a grooved face on the periphery of the wheel 19, either concave or convex, which is of a radius corresponding to the radius of the sphere to be ground. This may be accomplished by providing a radial truing device which in the present case comprises a radial truing supporting bracket 70 which is preferably supported to swing about a substantially vertical axis as a pivot. As illustrated in the drawing, the lower end of the pivotal support 50 is substan-

tially C-shaped and of proper dimensions to receive a substantially C-shaped radial truing bracket 70. A screw 71 is threaded into the lower arm of the C-shaped projection of the member 50. The screw 71 has a pointed end 72 which engages a mating aperture in the lower face of the bracket 70. The upper arm 73 of the C-shaped projection of the member 50 is provided with a bearing 74 which is adapted rotatably to support an upper frusto-conical bearing surface 75 on an upwardly extending supporting stud which is either fixedly mounted on or formed integral with the bracket 70. The axis of the frusto-conical bearing member 75 and the screw 71 together with its mating aperture 72 are arranged in axial alignment with each other and are arranged in a substantially vertical position. The radial truing bracket 70 serves as a support for a truing tool 76 which is adjustably supported on the bracket 70. The truing tool 76 is provided with a cylindrical portion which fits within a mating aperture in the radial truing bracket 70. The bracket 70 is provided with a slot 77 (Figs. 1 and 2) which extends through the bracket 70 adjacent to the truing tool 76. A clamping screw 78 passes transversely through the slotted portion of the bracket 70 and is threaded into a portion of the bracket and serves to lock the diamond or truing tool holder 76 in adjusted position on the bracket 70.

In order to facilitate operation of the radial truing device, a shaft 79 extends upwardly from the bearing surface 75 and is provided at its upper end with an actuating handle 79 by means of which the bracket 70 may be rocked about its supporting axis to traverse the diamond or truing tool 76 in an arcuate path to produce a peripheral groove in the operative face of the grinding wheel of the required radius. By adjusting the diamond or truing tool 76 relatively toward and from the axis of movement of the radial truing bracket 70, the radius of the groove produced by the attachment may be readily varied as desired.

It is desirable that a locking device be provided whereby the radial truing bracket 70 may be readily locked to the pivotally mounted support 50 so that during the traversing movement of the truing tool 76 in producing an irregular form on the wheel 19, the truing tool is held in a fixed position relative to the pivotally mounted traversable supporting member 50. As illustrated in the drawing, a locking mechanism may comprise a spring pressed plunger 80 having a frusto-conical end portion which engages a notch or groove 81 cut in the face of the radial truing bracket 70. When the pawl 80 is in the position illustrated in Fig. 1, the bracket 70 is held against an oscillating movement. When it is desired to true a radial surface or groove in the periphery of the wheel, the spring pressed plunger 80 is moved toward the left (Fig. 1) and rotated a partial turn to lock the pin out of engagement with the recess or groove 81 so that the radial truing bracket 70 may be oscillated by means of the manually operable handle 79 to produce a grooved face on the periphery of the grinding wheel of a predetermined radius.

A pair of adjustable stops 85 and 86 are provided on the dovetailed slide 40. These stops fit on the dovetailed slideway 40 and are adjustable longitudinally thereon and serve to limit the longitudinal traversing movement of the slide 41.

To facilitate setting the diamond or truing tool 76 so as to true a groove of a predetermined radius, a locating surface 90 is provided on the 75

5 pivotally mounted supporting frame 50. The locking plunger 80 is withdrawn and the handle 79 turned 180° from the position shown in Fig. 1 so that the radial truing bracket 70 and the supporting member 50 are positioned in the manner illustrated in Fig. 6. A gauge block 91 is then inserted in the gap between the locating surface 90 and the truing tool 76, after which the truing tool is adjusted laterally by releasing the clamping 10 screw 11a and turning an adjusting screw 92 to adjust the position of the truing tool 76 until it contacts with the surface of the gauge block 91. The gauge block 91 is of a predetermined size so that when the truing tool is adjusted in accordance with the location of the gauge block, the point of the truing tool 76 projects from the axis of rotation of the radial truing tool holder 70 by an amount equal to the radius of the spherical portion of the work piece to be ground and equal 15 to the radius of the groove to be generated on the periphery of the grinding wheel 19. After the truing tool 76 has been adjusted into proper position, the clamping screw 11a is tightened to lock the truing tool in its adjusted position.

20 25 The operation of this improved truing apparatus will be readily apparent from the foregoing disclosure. The truing tool 76 is first adjusted in the manner above described relative to the radial truing bracket 70 so that it will true the proper radius on the periphery of the wheel. The stop 85 on the dovetailed slide 40 is then adjusted so that when the truing tool 76 is traversed to its extreme left-hand position (Fig. 2), the stop 85 is adjusted so that when the slide 41 is traversed into engagement with it, the axis of rotation of the radial truing bracket 70 will lie in a plane passing through the axis of the groove to be generated upon the wheel periphery, so that when the grinding wheel is advanced toward the truing tool and 30 35 the truing tool 76 is slowly oscillated by means of the manually operable handle 79, the truing tool 76 will traverse in an arcuate path to produce a groove in the wheel periphery of a predetermined radius.

40 45 The stop 86 is adjusted longitudinally on the dovetailed slideway so that when the slide 41 is traversed in a direction toward the right (Fig. 2) into engagement with the stop 86, the truing tool 76 will be positioned as indicated in Fig. 5, slightly beyond the side face of the grinding wheel 19.

50 The truing device may be operated in two different manners; first, the slide 41 may be traversed toward the right (Fig. 2) until it engages the stop 86. The radial truing bracket is unlocked by withdrawal of the spring-pressed locking pin 80 and the radial truing device is rocked so that the truing tool 76 is in the position 76a (Fig. 3). In this position of the parts, the slide 41 may be traversed toward the left (Fig. 2) to shift 55 60 the apparatus into position for truing the groove in the periphery of the wheel. When the slide 41 of the truing apparatus has been moved into engagement with the stop 86, the handle 79 is rocked or oscillated to pass the truing tool 76 in an arcuate path across the wheel periphery. The grinding wheel may be advanced gradually during this part of the truing operation, until the wheel is stopped by the positive stop on the feeding mechanism, to true the groove 95 to the desired depth. 65 70 The grinding wheel 19 may then be backed off and the radial truing frame rocked to position the truing tool 76 in the position 76a, after which the slide 41 may be moved toward the right (Fig. 2) by rotation of the manually operable traverse wheel 45. When the slide 41 engages the stop 86,

75 the radial truing bracket 70 is swung into position (Fig. 5) and the locking pin 80 is positioned to lock the bracket 70 to the pivotally mounted supporting bracket 50, so that the diamond or truing tool 76 is in the position illustrated in Fig. 5. The grinding wheel 19 may then be advanced gradually until stopped by the infeed stop and the slide 41 is traversed toward the left (Fig. 2) by rotation of the traverse wheel 45, during which time the follower 60 follows the shape on the 10 forming bar 61 and the diamond trues a frusto-conical surface 96 and rounds the corner 96a between the frusto-conical surface 96 and the groove 95 and then, due to the shape of the forming bar, the diamond or truing tool is moved 15 away from the groove of the wheel, thus generating a groove on one portion of the wheel and then producing an adjacent frusto-conical surface with a rounded edge portion therebetween.

20 25 If desired, the wheel may be trued by first truing the groove to a slight extent, then shifting the radial truing frame 70 and traversing the same to an extreme right-hand position (Fig. 2), after which the diamond may be passed to true a corresponding amount off the frusto-conical surface 25 30 35 40 45 50 55 60 65 70 75 80 85 90 95 100 105 110 115 120 125 130 135 140 145 150 155 160 165 - port for said device which supports said radial truing device with its axis in a substantially vertical position, means to lock said device to said support to render said radial truing device either operative or inoperative, means including a manually operable nut and screw mechanism to traverse said support longitudinally, and means including a forming bar and a follower to move said support transversely so as to produce a predetermined form on the operative face of a grinding wheel. 5
4. In a grinding wheel truing device, a truing tool, a pivotally mounted radial truing device to support said tool, a transversely movable support for said device which supports said radial truing device with its axis in a substantially vertical position, means to lock said device to said support to render said radial truing device either operative or inoperative, means including a forming bar 10 and a follower to move said support transversely, means to locate said support in a predetermined position to locate said radial truing device for truing a groove in a predetermined position on the wheel face, and means to traverse said support to produce a predetermined form on said wheel face adjacent to said groove. 15
5. A grinding wheel truing apparatus comprising a base, a longitudinally movable slide thereon, a manually operable nut and screw mechanism to traverse said slide longitudinally relative to said base, a pivotally mounted supporting member on said slide, said pivot being arranged in a substantially horizontal position, a forming bar and a follower one of which is carried by the supporting member and the other by the base, a pivotally mounted radial truing device pivotally supported on said supporting member with its axis in a substantially vertical position, manual means to oscillate said radial truing device to 20 true a circular groove on the operative face of a grinding wheel, and a manually operable locking device to render said radial truing device inoperative when the slide is traversed to true a formed surface on the grinding wheel. 25
- 45 6. A grinding wheel truing apparatus having a base which is arranged to be clamped upon a grinding machine table, an upper base member adjustably mounted thereon, a longitudinally movable slide on said upper base member, a manually operable nut and screw mechanism to traverse said slide longitudinally relative to said base, a supporting member pivotally mounted on said slide and arranged to pivot about a substantially horizontal axis, a forming bar and a follower one of which is carried by said member and the other by the upper base, yieldable means to maintain said follower and bar in operative contact with each other, a pivotally mounted radial truing device pivotally supported on said member with its axis arranged substantially in a vertical position, a truing tool adjustably supported on said device, manual means to oscillate said radial truing device, means including an adjustable stop to locate said slide in a predetermined position for truing a groove in the operative face of a grinding wheel, and a manually operable locking device to render said radial truing device operative or inoperative as desired. 10 15 20 25 30 35 40 45
7. A grinding wheel truing apparatus comprising a base adapted to be clamped onto a grinding machine table, an upper base member adjustably mounted thereon, a longitudinally movable slide thereon, a manually operable nut and screw mechanism to traverse said slide longitudinally relative to said base, a supporting member pivotally mounted on said slide, a forming bar and a follower one of which is carried by said member and the other by the upper base, yieldable means including a spring acting upon said member to maintain said follower and bar in operative contact with each other, a pivotally mounted radial truing device pivotally supported on said member with its pivotal axis in a substantially vertical position, a truing tool adjustably supported on said device, manual means to oscillate said radial truing device to true a groove in the operative face of a grinding wheel, and a manually operable locking device to render said radial truing device operative or inoperative as desired. 15 20 25 30 35 40 45
8. In a grinding wheel truing apparatus, an adjustably mounted truing tool, a pivotally mounted radial truing device to support said truing tool, said radial truing device being pivotally supported on a substantially vertical axis, a pivotally mounted support for said device, means to traverse said support longitudinally, means including a forming bar and a follower to rock said support to produce a predetermined formed face on a grinding wheel, means to lock said radial truing device to said support during the formed truing of said wheel, and an adjustable stop to limit the movement of said support in one direction to position the axis of said radial truing device in a predetermined position to true a groove in the operative face of said grinding wheel adjacent to said formed face. 40 45

CARL G. FLYGARE.
